United States Patent Office

Des. 178,737
Patented Sept. 11, 1956

178,737

FILING CABINET

Richard P. Scholfield, Armonk, N. Y.

Application January 17, 1955, Serial No. 34,003

Term of patent 14 years

(Cl. D74—1)

Fig. 1.

Fig. 2.

I claim:

The ornamental design for a filing cabinet, substantially as shown.
